US00D773643S

(12) **United States Design Patent** (10) **Patent No.:** **US D773,643 S**
Luzbetak et al. (45) **Date of Patent:** **** Dec. 6, 2016**

(54) **SELF RETURNING CONTAMINATION BARRIER**

- (71) Applicant: **Medela Holding AG**, Baar (CH)
(72) Inventors: **Mark A. Luzbetak**, Kildeer, IL (US);
Thomas A. Sutrina, Rockford, IL (US);
Erich Pfenniger, Ebikon (CH); **Patrik Bosshard**, Buonas (CH)
(73) Assignee: **Medela Holding AG**, Baar (CH)
(**) Term: **15 Years**
(21) Appl. No.: **29/530,623**
(22) Filed: **Jun. 18, 2015**

Related U.S. Application Data

- (60) Continuation of application No. 13/269,381, filed on Oct. 7, 2011, which is a division of application No.

(57) **CLAIM**

The ornamental design for a self returning contamination barrier, as shown and described.

DESCRIPTION

FIG. 1 is a perspective view of a self returning contamination barrier showing the design.

FIG. 2 is a front view of the design of FIG. 1.

FIG. 3 is a back plan view of the design of FIG. 1.

FIG. 4 is a side view of the design of FIG. 1.

FIG. 5 is another side view of the design of FIG. 1.

FIG. 6 is a top plan view of the design of FIG. 1.

FIG. 7 is a bottom view of the design of FIG. 1.

FIG. 8 is a side view of the design of FIG. 1 in an alternate position with the center depressed; and,

FIG. 9 is a side view of the design of FIG. 1 in an alternate position with the center extended.

The broken lines in the drawings illustrate portions of the self returning contamination barrier which form no part of the claimed design.

1 Claim, 5 Drawing Sheets

Related U.S. Application Data

11/591,276, filed on Nov. 1, 2006, now Pat. No. 8,187,227.
